UNITED STATES PATENT OFFICE.

RASMUS M. HVID, OF CHICAGO, ILLINOIS.

FUEL-SUPPLY VALVE.

Application filed September 1, 1921. Serial No. 497,730.

To all whom it may concern:

Be it known that I, RASMUS M. HVID, a citizen of the United States, and a resident of Chicago, in the county of Cook and State 5 of Illinois, have invented certain new and useful Improvements in a Fuel-Supply Valve, of which the following is a specification.

My invention relates to internal combustion engines of the type in which ignition is effected by the heat of compression and in which liquid fuel is inhaled during the suction stroke of the cycle.

One of the objects of my invention is to 15 provide means in connection with the fuel supply for abstracting heat from the valve body at a point adjacent to the ignition cup.

It has been found in practice that in the use of certain grades of liquid fuel the heat 20 absorbed by the cup and valve body serves to volatilize sufficient of the fuel to form a gas pocket of such volume as to displace the liquid fuel and finally cause the stoppage of the engine. To obviate this it has been found 25 to be desirable to effect a circulation of liquid fuel at a point adjacent to the valve body, thereby withdrawing sufficient heat to maintain the parts in proper operating condition.

30 In the construction here proposed I provide a chamber which surrounds the valve body at a point intermediate its ends, the chamber being in communication with the needle valve passage and pipe connections 35 being provided for the supply and discharge of liquid fuel to the chamber. In addition I have provided means for simple and effective control of the needle valve, the details of which will be hereinafter described.

40 The invention will be more readily understood with reference to the accompanying drawings, in which,

Fig. 1 is a longitudinal vertical sectional view through a fuel supplying device constructed in accordance with my invention, and,

Fig. 2 is a plan view thereof.

In the drawings it will be seen that a cylinder 10, is provided with a head 11, having a vertical cylindrical recess 12, provided at its lower end with a tapering seat 13. Mounted within the recess 12 is a valve body 14, having a flanged head 15, engaged by the nuts 16, for the purpose of securely holding 50 the body in place. An ignition cup 17 is secured to the lower end of the valve body, 55

the cup being provided with a tapering surface adapted to engage with the seat 13, in order to make a fluid-tight joint. The valve body is concentrically apertured to 60 provide for a valve 18, having a stem 19 and operated through the medium of a plunger 20, by a bell crank 21. The valve body is also diagonally apertured to provide for a needle valve 22, the pointed lower end of 65 which enters the contracted passage 23, through which the liquid fuel is supplied in measured quantities to the ignition cup 17. The upper end of the needle valve has a spherical portion 24, which engages with 70 a threaded stem 25, terminating in a nurled nut 26. A spring 27 backs up the spherical end of the needle valve within the stem. The stem is mounted within a threaded opening in a similarly threaded sleeve 28, 75 to which is secured an arm 29, operating on a sector 30, as best shown in Fig. 2. The threaded portion of the sleeve 28 is mounted within a threaded aperture in a rigid portion 31 of the valve body. The arrangement 80 is such that as the arm 29 is swung through its limit of movement, the needle valve is raised and lowered to open and close the needle valve opening. The fine adjustment of the needle valve is secured by means of 85 the threaded stem 25.

The valve body 14 is cut away at a point intermediate its ends thereby providing a chamber 32 which is in communication with the diagonal passage within which the needle 90 valve is mounted. Threaded openings 33, 34, provide for pipe attachments, the former serving to admit liquid fuel and the latter to discharge the excess. In practice the fuel pump (not shown) will deliver liquid fuel 95 through the lower opening and cause its discharge through the upper opening whereby a constant circulation is maintained through the chamber 32. This serves to abstract surplus heat and maintain the valve 100 body in a proper condition as to temperature. Another advantage in the construction described is in that the valve body and its connected parts may be inserted and removed without interfering with any pipe 105 connections. This simplifies the matter of operation very materially and reduces the time required for removal and replacing of the valve. Furthermore, the cooling medium is applied to the valve body at a point close 110 to that at which the greatest heat is found; that is, within the ignition cup. The exact

temperature for best operating conditions may be attained by regulating the speed of the pump to circulate the cooling medium in proper quantities.

5 It will be noted that sufficient space is provided around the measuring pin for the escape of any trapped air or gas which may accumulate in the chamber. It will be noted also that the spring separating the measuring pin from the adjusting stem serves the purpose of preventing the jamming or distorting of the valve seat, due to the action of the arm in opening and closing the valve. This is a useful provision and avoids considerable difficulty particularly in multi-cylinder engines.

Obviously the construction is capable of modifications and I do not wish to be limited except as indicated in the appended 20 claims.

I claim:

1. In an internal combustion chamber of the type in which liquid fuel is supplied for combustion purposes, the combination of a 25 cylinder, a valve adapted to be seated in said cylinder and provided with a reduced intermediate portion, said cylinder being provided with inlet and outlet ports communicating with the space formed by said 30 reduced portion whereby liquid fuel may be caused to circulate around said valve body.

2. In an engine of the type in which liquid fuel is employed for combustion, the combi-

nation of a cylinder having a recess, a valve 35 body adapted to occupy said recess, said valve body being cut away to provide a chamber between the body and the adjacent wall of the cylinder, and inlet and outlet passages for liquid fuel communicating with 40 said chamber whereby liquid fuel is caused to circulate through said chamber.

3. In a fuel-supplying and circulating device, the combination with a cylinder having a recess, of a valve body adapted to occupy 45 said recess and having a needle valve passage, said valve body being reduced to provide a chamber in communication with said passage, the cylinder wall having inlet and outlet ports whereby liquid fuel is caused to 50 be supplied to said chamber and to circulate therethrough for the purpose of abstracting heat from said valve body.

4. A fuel-supplying and circulating device, comprising in combination a cylinder 55 having a recess, a valve body adapted to occupy said recess and having a needle valve passage, a chamber being provided between a wall of said cylinder and said valve body, said chamber being in communication with 60 said passage and having inlet and outlet ports whereby liquid fuel is caused to be supplied to said chamber and to circulate therethrough for the purpose of withdrawing heat from said valve body. 65

Signed at Chicago, Illinois, this 26th day of August, 1921.

RASMUS M. HVID.
